RAZOR STROPPING AND SHARPENING MECHANISM.

1,081,283.

Specification of Letters Patent.

Patented Dec. 9, 1913.

Application filed May 25, 1906. Serial No. 318,619.

To all whom it may concern:

Be it known that we, LEON A. FLINKER, a citizen of the United States, and a resident of the borough of Manhattan, in the city, county, and State of New York, and JOHN SCHADE, Jr., a citizen of the United States, and a resident of the borough of Brooklyn, in the city of New York, county of Kings, and State of New York, have jointly invented a certain new and useful Improvement in Razor Stropping and Sharpening Mechanism, of which the following is a specification.

This invention is a razor sharpening machine, and it embodies, mainly, means whereby the respective lengths of a strop are deflected inwardly toward a movable blade holder, whereby the strop is presented in a proper manner to the blade in said holder for the purpose of sharpening the respective edges of the blade, all as will be hereinafter set forth.

Referring to the accompanying drawings which forms a part of this specification, Figure 1, is an end elevation of a stropping and sharpening mechanism constructed in accordance with one form of our invention, portions of the strop being broken out for convenience of illustration, with a razor blade adjusted in place for stropping and sharpening and the parts of the mechanism in the positions they occupy when the stropping and sharpening operation is being effected. Fig. 2, a similar end elevation of such mechanism, with a razor blade adjusted in position for stropping and sharpening, but with certain of the parts of the mechanism separated or swung apart, as when the razor is to be applied to or removed from it, and the strop in like manner broken away; Fig. 3, a side elevation of the stropping and sharpening mechanism, with a razor blade adjusted in place for stropping and sharpening, and the handle of the razor and the strop similarly broken away; Fig. 4, a similar side elevation of the stropping and sharpening mechanism on an enlarged scale, with the strop omitted, certain of the parts shown in section; Fig. 5, an enlarged vertical transverse section of the stropping and sharpening mechanism, and of a razor blade held therein taken in the plane $x-x$ of Fig. 4, the strop being shown and likewise broken away; Fig. 6, is

a side elevation of auxiliary jaws for aiding the main holding jaws in holding a safety razor blade of the Gillette or other similar form, detached, parts being broken away to show the adjustment of the razor blades therein, and the razor blade being also illustrated in side elevation, and Fig. 7, a transverse section of the auxiliary jaws and razor blade taken in the plane $y-y$ of Fig. 7, and showing their arrangement within the main holding jaws during the stropping and sharpening operation, the said main holding jaws being also shown in transverse section in a plane corresponding to that indicated by line $x-x$ of Fig. 4.

In all the figures, like letters of reference are employed to designate the corresponding parts.

A indicates a base of an appropriate frame upon which the various parts of the mechanism are or may be supported, and B indicates the strop by means of which the stropping and sharpening of the razor blade are effected. In the embodiment of the invention selected by us for purposes of illustration, this base A is preferably constructed in plate form, with its opposite ends bent downward or inward at approximate right angles to form ears a and a^1 , and is provided on its back with a ring a^2 , or other convenient appliances, through which the mechanism may be supported and held during the stropping and sharpening operation.

Pivoted between the ears a and a^1 on the base A, by pivots b and b^1 , are the devices C by which the holding of the razor blade during the stropping and sharpening operation is effected. These devices, which may be constructed in various forms, are here shown as composed of a cylindrical shaft b^2 , with two arms b^3 and b^4 extending therefrom, and as carrying at their outer free ends the holding jaws b^5 , between which the clamping of the razor blade is effected. In the construction of these holding devices the arms b^3 and b^4 may be made either separate from, or integral with, the shaft b^2 , and the trunnions b and b^1 may in like manner be formed integral therewith, or separable therefrom, as may be preferred. In the drawings however we have shown the arms b^3 and b^4 as made integral with the shaft b^2 , as we have also shown the pivot or trunnion b , as made

integral therewith. The pivot or trunnion b^1 , on the other hand, is depicted as made separable therefrom in the form of a screw, which is passed through a suitable orifice formed in the ear a^1 and engages at its inner end with a correspondingly shaped threaded orifice formed in the end of the shaft b^2 , as is clearly apparent from the drawing. These various constructions and arrangements of parts however are merely illustrative, and other and different forms of construction and arrangement may be adopted in place thereof if so preferred. The jaws b^5 may, in like manner, be modified in various ways. We prefer however to construct them in the form of gradually approaching plates, which project forward from a suitable back plate b^6 , in a slightly curvilinear contour, and are or may be provided near their middle portions with recesses, whereby to permit of access to the razor blade at that part when required, but this is unessential and the jaws may be made without such recesses, if desired. As thus constructed and arranged, these razor holding devices, as will be seen, are not only supported upon the base A, of said supporting frame, but are capable of a back and forth vibrating movement thereon, as the exigencies of the stropping and sharpening operations may require, and in order to return these devices to a position intermediate the limits of their vibratory movement, and hold them therein when a razor blade is being inserted between or withdrawn from them, we make use of a spring D, which, in the example of the invention shown in the drawing, is made in the form of a plate that is secured at one of its ends to the inner side of the base A, by screws or rivets c, with its free end bent downwardly or inwardly and engaging at its outer extremity with a flattened surface a^1 formed on the back of the cylindrical shaft b^2 , as shown. By this arrangement, as will be seen, the return of the razor holding devices to their middle normal position is automatically effected whenever vibrated therefrom and the vibrating forces are withdrawn.

For adapting the razor blade holding devices to hold and retain blades of different widths and forms during the stropping and sharpening operation, and insure of the cutting edges of the blades being projected outwardly from the jaws b^5 to approximately the same distance, whatever their width or form may be, various means may be employed. We prefer however, to employ for this purpose a bar or plate b^7 , which, secured at one of its ends to the back plate b^6 by screws or otherwise, and extending outwardly in its central portion away from such plate and made capable of flexure, is provided at its other end with a block or abutment b^8 , against which bears the inner

end of an adjusting screw b^9 , that is properly threaded in a suitable orifice formed in the arm b^4 , and is provided at its outer end with a suitable milled or otherwise constructed head whereby its rotation in one or the other direction may be effected as may be desired. With the bar or plate b^7 and the screw b^9 thus arranged, and a razor blade of the ordinary form inserted in proper position between the jaws b^5 , the securing and holding of the blade between these jaws will be effected by forcing the middle portion of the bar or plate b^7 outward against its back, by turning the screw b^9 in the proper direction to cause such movement, when the blade will be pressed outward between the jaws and firmly held thereby, with its cutting edge projecting therefrom to the requisite degree for the stropping and sharpening operation, as shown in Fig. 5. On the other hand, when a safety razor blade of the "Gillette," or other similar form without an enlarged back is to be held for the stropping and sharpening operation, then, instead of such blade being held by the direct action of the jaws b^5 thereon, auxiliary jaws b^{10} are required, see Figs. 6 and 7 which are made of the proper form to receive and hold the different forms of safety razor blades of this class, and at the same time be themselves received within and held by the main jaws b^5 . These auxiliary jaws may be of various constructions. In Figs. 6 and 7 we have shown one of the various examples that may be employed for this purpose, the same being composed of two jaws b^{10} , hinged together at their backs whereby their free front edges may be swung toward and away from each other, with their inner sides made of the proper shape or contour to receive the razor blades, and their exterior surface constructed of a form to fit between and be held by the jaws b^5 , as shown.

With the auxiliary jaws constructed as thus explained, the holding of the razor blade of the Gillette, or other similar form, will be effected by inserting the closed auxiliary jaws b^{10} between the jaws b^5 , with the razor blades arranged between the former, and forcing these auxiliary jaws b^{10} outward between the jaws b^5 , by turning the screw b^9 in the proper direction, when the middle or central portion of the bar or plate b^7 will be forced outward, carrying with it the auxiliary jaws and the razor blades clamped between them, with the result that the auxiliary jaws and their contained razor blade will be firmly clamped between the jaws b^5 , as will be readily understood.

While the auxiliary jaws thus far described are constructed more particularly for holding safety razor blades of the form that are unprovided with thickened or enlarged backs, and while the Star or other similar

forms that are provided with such backs may be held directly by the jaws b^5 , the auxiliary jaws may be constructed of such form as to hold these enlarged or thickened back blades without other adaptation than a mere fabrication of their parts of the requisite form and size to receive them. On the other hand, when blades of the Gillette and other forms of safety razor similar to them with oppositely arranged cutting edges and an aperture or apertures formed through their body portions are to be held therein during the stropping and sharpening operation, without the rear cutting edge being brought in contact with any dulling surface, then we provide one of these auxiliary jaws b^{10} with a stud or plurality of studs b^{11} , projecting inward from its inner side at the proper position or positions to engage with the aperture or apertures in the blade, and thereby hold such blade thereon when such auxiliary jaws are clamped between the jaws b^5 .

With the holding devices constructed and operating as above explained, the holding of the razor blades of the various forms may be effected, during the stropping and sharpening operation, and the cutting edges thereof projected from the jaws b^5 to approximately the same distance whatever the widths of the blades may be.

For supporting and guiding the strop and for bringing the sides of the edge of the razor blade against it, as such strop is reciprocated back and forth past them to effect the stropping and sharpening operation, various means may be employed. As shown, the main supporting frame is provided with movable end frame members, E, which are adapted to be opened or spread for more conveniently inserting a razor blade into the blade holder, and for removing the blade from said blade holder; but after inserting the blade and prior to starting the stropping operation, said movable end members, E, of the frame should be closed, and they should remain closed during such stropping operation. As shown, the end members, E, of the frame are mounted upon the pivots b and b^1 of the shaft b^2 , and we tie them together and hold them at the proper distance apart by rods extending across between them, using these rods at the same time to guide the strop B.

In some instances these end members, E, of the frame may each be made of a single piece, and, when such construction is employed, the same relationship of its various parts with respect to one another are maintained therethrough. We prefer however to construct each of these end members of the frame of two separate and distinct parts e and e^1 , of the form shown in the drawing, and to pivot the upper ends of the parts of each of these end members together upon the

respective pivot b or b^1 , as thereby not only may the plies of the strop be brought in close relationship to the razor blade and held in that position during the stropping and sharpening operation, as shown in Figs. 1 and 5, but such plies, with the parts e and e^1 of the end members, E, of the frame may be opened or separated from each other when it is desired to insert or remove a razor blade from the holding devices C, as shown in Fig. 2. With the end members, E, of the frame E thus severally made up from two parts e and e^1 , the corresponding parts e of the two end members of the frame are preferably tied together and held at the proper distance apart by the rods e^2, e^3, e^4 , and e^5 , while the corresponding parts e^1 are similarly tied together and held at the proper distance by rods e^6, e^7, e^8 , and e^9 . Of these various rods, the rods e^2 and e^6 are arranged near the upper ends of the respective parts e and e^1 , on opposite sides of the shaft b^2 , while the rods e^3 and e^7 of these respective parts are located below the rods e^2 and e^6 , midway the lengths of the parts, and at points slightly above where the side of the edge of the razor blade held in the holding devices C will contact with the strop when such razor blade is swung toward and against it.

The rods e^4 and e^8 , on the other hand, are disposed immediately below the respective rods e^3 and e^7 of the parts e and e^1 , near the lower ends of these parts, and the rods e^5 and e^9 are arranged between the respective rods e^4 and e^8 and approximately on the same line therewith in the lower ends of their respective parts e and e^1 .

With the rods disposed as thus explained, the strop B, when applied to the other mechanism and in position for use, is passed upward between the rods e^4 and e^5 , thence upward and slightly outward over the rods e^3 , thence over the rod e^2 , thence downward and under the shaft b^2 , thence outward and upward over the rod b^6 , thence inward and downward against the inner side of the rod e^7 , and thence downward between the rods e^8 and e^9 . As thus arranged and supported by the various rods and the shaft b^2 , the movement of the strop back and forth in the direction of its length, and the vibration of the razor blade back and forth to bring the sides of its edge in contact therewith, may be effected by simply drawing first on one of its ends and then on the other, while its opposite plies are guided past the blade and prevented from moving laterally toward it beyond certain limits by the respective rods e^5 and e^9 , extending across from one end frame to the other on the inner sides of such plies; and in order to reduce the friction opposed to the movement of the strop back and forth over the various supporting and guiding rods, we preferably provide

each of these rods with a sleeve e^{10} , which is rotatively mounted thereon, as shown.

From the foregoing description it is manifest that base, A, and end members, E, constitute a supporting frame which carries the devices for guiding strop, B, and supporting blade holder, C, in cooperative relation to said strop, B. The particular form of said frame, comprising parts, A, E, E, for supporting the working parts of the sharpening machine, may, however, be modified or changed, as desired.

A characteristic feature of this invention consists of strop supporting guides, such as 15 e^7, e^8 , carried in the supporting frame between a pair of guides, e^2, e^6 , at the rear end of said frame and other guides, e^4, e^5 , and e^8, e^9 , at the front end of said supporting frame, said guides, e^7, e^8 , occupying positions substantially in the rear of the points 20 where the blade in holder, C, is adapted to be engaged with strop, B. Were guides, e^7, e^8 , omitted, the leads of strop, B, would be unsupported between guides, e^2, e^4 , on one 25 side of the supporting frame, and, also, between guides, e^6, e^8 , on the other side of said supporting frame, hence the unsupported parts of strop, B, would yield or give outwardly when the blade is pressed by the action 30 of holder, C, into contact with the inner faces of strop, B. The employment of guides, e^7, e^8 , in positions between the pairs of guides positioned at the respective ends of the supporting frame, overcomes this outward deflection of said strop at the particular 35 places where the blade engages with the leads of strop, B, for the reason that said guides, e^7, e^8 , resist the pressure of the blade and "back up" the strop at such points of engagement between the blade and the strop. Furthermore, the guides, e^7, e^8 , deflect the strop inwardly toward the sides of the blade in the holder, such deflection occurring rearwardly of the front edge of the blade, and 40 resulting in the strop being presented at an angle to the edge of the blade so as to secure a proper sharpening effect on said edge of the blade.

In the construction of the strop B, any appropriate material may be employed, or one 50 surface made of one material and the other of another, as, for instance, one side of leather and the other of canvas. We prefer however to employ for the purpose leather having 55 its opposite abrading surfaces of different degrees of fineness, and to provide the strop at its opposite ends with rings or handles h and h^1 , whereby they may be engaged and held by the hands of the operator, and the back and forth reciprocation of the strop effected through them. With the strop thus made with its opposite abrading surfaces of different degrees of fineness, the strop may be inserted in the supporting and 60 guiding mechanism in such a manner as to

bring either surface inward in operative relationship to the razor blade, and the change from one surface to the other may be effected by simply withdrawing the strop from such mechanism and after reversing it side for side again inserting it therein, when the desired surface may be brought opposite the blade; and in order to permit of the insertion and withdrawal of the strop in the supporting and guiding mechanism and for reversing it side for side, we find it desirable to so secure one of the rings or handles, as, for instance, the handles h , to the end of the strop as to render it detachable therefrom, and, for this purpose, we secure the ring or handle thereto by means of a strip or strips h^2 , bent around the ring or handle, overlapped upon the opposite sides of the strop, and secured thereto by means of a bolt or bolts h^3 or other appropriate appliance, as 70 75 80 85 shown in Fig. 1.

With the parts constructed and arranged as above explained, and the strop properly inserted in place in its supporting and guiding frame, the operation of the mechanism is 90 as follows: The mechanism will first be secured to any suitable or appropriate support, and the frame is opened by swinging the members, E, thereof outwardly upon their pivots away from each other by carrying outward the ends of the strop, and the razor blade, F if of the ordinary form, is inserted between the jaws b^5 , with the handle downward, and properly adjusted therein by turning the screw b^9 in the required 95 direction to force it outward through the flexure of the bar or plate b^7 until it contacts at its sides with, and is arrested in movement by, them. The razor blade having been thus secured in place, the end members, E, of the frame, with the several rods supported in said end members, will be 100 swung together toward each other upon their pivots b and b^1 , by bringing the ends of the strop together, and the strop then reciprocated back and forth in the direction of its length, the result of which operation coupled with the friction of the strop on the shaft b will be to cause the razor and its holding devices to be swung back and 105 forth on their pivots, and thereby bring first one side and then the other side of the edge of the razor blade in contact with the strop, and hold it in one and the other of those 110 positions, as the strop is reciprocated back and forth in one and the other direction. The reciprocation of the strop thus initiated will be continued until the razor blade has been stropped and sharpened to the required degree, when the end members, E, of 115 the supporting frame, together with the rods supported in said frame members, E, will be again swung away from each other, by carrying outward the opposite ends of the 120 strops and the razor then removed from the 125 130

mechanism by simply drawing it out in the direction of its length from the jaws b^5 .

The operation necessary to the stropping and sharpening of an ordinary razor blade 5 will be repeated when a razor blade F^1 of a Gillette or other similar form is to be stropped and sharpened, with the exception that instead of the blade being inserted directly between the jaws b^5 of the holding devices, it will be first adjusted between the auxiliary jaws, with the aperture or apertures in its body placed upon the stud or studs b^{11} , and the auxiliary jaws then inserted between the jaws b^5 , when the secure- 10 ment of these parts between the jaws b^5 will be effected by turning inward the screw b^9 as shown in Fig. 7.

Although in the preceding we have described our auxiliary jaws and their combination with the razor stropping and sharpening mechanism, we make no claim thereto 20 herein, as the same will form the subject of a separate application to be hereafter filed.

With the parts constructed and arranged 25 as above described, a razor stropping and sharpening mechanism is produced, which, while simple in construction and convenient in operation, is, at the same time, highly efficient in operation, and permits of the stropping and sharpening of a razor blade by an inexperienced person or novice with the same facility and ease as by a person highly skilled in the art.

While in the foregoing we have described 35 the best means contemplated by us for carrying our invention into practice we wish it distinctly understood that we do not limit ourselves strictly thereto, as it is obvious that we may modify the same in various 40 ways without departing from the spirit of the invention.

Having now described our invention, and specified certain of the ways in which it is or may be carried into effect, we claim and 45 desire to secure by Letters Patent of the United States:—

1. In a razor sharpening device, a frame, a movable blade holder, a strop, two strop guides at one end of said frame, other guides 50 at the opposite end of said frame, and rollers intermediate the respective ends of said frame, said rollers operating to direct the respective lengths of the strop inwardly with respect to the frame and at points 55 intermediate the ends of said frame.

2. In a razor sharpening device, a frame, a movable blade holder, a strop, two rollers at one end of said frame, two pairs of rollers at the opposite end of said frame, and additional rollers intermediate the said rollers 60 at the respective ends of the frame, said additional rollers operating to support the respective lengths of the strop at points intermediate the ends of the frame and operating, also, to deflect said lengths of the 65 strop inwardly toward the positions adapted to be assumed by the blade holder.

3. The combination of a back plate or support, a shaft pivoted thereto and carrying blade-holding devices, end frame members pivoted to said back plate or support, said frame members being adjustable relative to said blade-holding devices, a connecting rod located on each side of said shaft and in the upper portion of said frame 70 members, said rods being separate from the pivotal connections between the frame members and the back plate or support, the upper surface of said rod being above the under surface of said shaft and extending across 75 from one end frame member to the other, and a strop arranged over such rods and under the shaft, said strop having frictional engagement directly with the shaft, substantially as described.

4. The combination, with a razor blade holding device constructed with a base plate and two jaws extending outward therefrom and gradually approaching each other at their outer ends, of a flexible plate arranged 90 in such holder, and an adjusting screw acting upon such flexible plate to cause its middle portion to flex more or less to adapt the holder to hold razor blades of different widths and forms, substantially as described. 95

5. The combination, with the back plate or support, and a shaft carrying the razor blade holding devices and provided with a flattened surface, of a spring carried by the said back plate or support and bearing at its 100 free end upon such flattened surface, whereby to return such shaft to its middle or normal position with the razor holding devices when rotated therefrom, substantially as described.
